UNITED STATES PATENT OFFICE.

NORBERT KOCH, OF ESSEN-RELLINGHAUSEN, GERMANY, ASSIGNOR, BY MESNE ASSIGNMENTS, TO THE ALIEN PROPERTY CUSTODIAN.

DEVICE FOR ADJUSTING THE RECOIL LENGTH OF FLUID BRAKES FOR GUN CARRIAGES.

1,417,922.

Specification of Letters Patent. Patented May 30, 1922.

Application filed February 3, 1915. Serial No. 5,900.

To all whom it may concern:

Be it known that I, NORBERT KOCH, residing at Essen-Rellinghausen, Germany, a citizen of the German Empire, have invented a 5 certain new and useful Improvement in Devices for Adjusting the Recoil Length of Fluid Brakes for Gun Carriages, of which the following is a specification.

The present invention relates to fluid recoil 10 brakes for gun carriages of the same character as those described in the copending application for Letters Patent Serial No. 822,656 filed March 5th, 1914, that is gun carriages having a device for adjusting the 15 recoil length according to the elevation of the gun and for varying the cross section of the fluid passages. The object of the present invention is now the further improvement of such devices.

20 One embodiment of the present invention is illustrated in the accompanying drawing where—

Figure 1 shows a longitudinal section of the brake piston and a portion of the cylinder; 25

Figure 2 a section along line 2—2 of Figure 1 seen from the left;

Figure 3 a section along line 3—3 of Figure 2;

30 Figure 4 a section along line 4—4 of Figure 3, seen from the left;

Figure 5 a section along line 5—5 of Figure 1 seen from the left;

35 Figure 6 a section along line 6—6 of Figure 3 seen from the left and—

Figure 7 a diagrammatic representation of the brake in smaller scale.

The piston head B having a hollow chamber b^2 and a piston rod B^1 is guided in the 40

brake cylinder A. On the inner wall of the brake cylinder A are cut two pairs of longitudinal grooves a^1 and a^2 , which follow a

45 screw line of such pitch that one end of each groove is displaced relative to its other end

an amount which corresponds to the width of the groove in question. The grooves a^2 have about twice the width of the grooves a^1 .

For connecting the grooves a^1 and a^2 with the fluid in front and rear of the piston head 50 B, are provided two pairs of apertures b^3 b^4 in the piston head having the same width

on the cylindrical surface of the piston head as the grooves a^1 , measured transversely to the longitudinal direction of the brake. To

55 insure that the fluid only proceeds by way

of the apertures b^3 , b^4 from one side to the other of the piston head, there are provided on the latter two revoluble but non-slidable rings C, C^1 having studs c^2 and c^3 engaging in the grooves a^1 and a^2 , and being secured 60 in place by means of nuts b^5 and b^6 .

When the apertures b^3 , b^4 have the position shown particularly in Figures 5 and 7 relative to the grooves a^1 , a^2 , corresponding to the hatched position I in Figure 7, the recoil of the piston B taking place in the direction of the arrow x , the brake fluid then proceeds from the piston rod side of the brake cylinder through the grooves a^1 and a^2 and the apertures b^3 , b^4 to the other side 70 of the piston. As the piston apertures then, in consequence of the helical form of the grooves a^1 , a^2 , are gradually covered by the inner wall of the brake cylinder, or in other words, that the sectional area at the place, 75 where the fluid is transmitted from the grooves a^1 , a^2 into the piston apertures, becomes more and more restricted, the fluid will then be gradually throttled. When finally the apertures b^3 , b^4 are completely 80 covered by the inner wall of the cylinder, see position II in Figure 7, no more fluid will then be able to pass. The recoiling parts will therefore be arrested. This, however, takes place only after the piston has completed its full (normal) stroke, that is the 85 longest recoil, as a consequence of the size of the grooves a^1 and a^2 .

In the above described setting of the brake, the area of the orifice for the brake fluid is, 90 towards the end of the recoil, comparatively great, so that the brake pressure does not exceed the amount, which is permissible for the rapidly decreasing stability of the carriage during the recoil of the gun under slight elevation.

95 If a recoil is desired, the length of which amounts to about half of the normal length, the piston rod has then to be turned by hand or automatically in the direction of 100 the arrow y , Figure 5, an angle which corresponds to the width of the grooves a^1 . The apertures b^3 are then completely covered by the inner wall of the brake cylinder, whilst the apertures b^4 take the position relative to 105 the grooves a^2 represented by dot and dash lines in Figure 6. In Figure 7 is the corresponding position of the apertures indicated by III. For the transmission of the brake fluid at the beginning of the recoil is then 110

only available the sectional area formed by the apertures b^4 which, during the recoil become gradually restricted, and at last completely closed, when the apertures b^4 have reached the position relative to the grooves a^2 , denoted by IV in Figure 7. As no transmission of the brake fluid is any longer possible, the moving parts will become arrested. As a consequence of the covering of the apertures b^3 by the inner wall of the brake cylinder, it has been attained that the sectional area for the brake fluid during the shortest recoil is less than during the longest recoil. The shape of the apertures b^4 has therefore been so selected, that when these apertures have been closed, the recoil energy will be completely exhausted.

Besides the normal recoil length and the one which will obtain with the last described setting of the brake, it will be obvious, that any other recoil length between the permissible shortest and the normal length, may be had, by corresponding adjustment of the piston rod.

25. I claim:

1. A device for adjusting the recoil length in fluid recoil brakes, having a piston and a part cooperating with the piston, said part being provided with a primary helical groove and a secondary helical groove, and said piston with a primary aperture and a secondary aperture corresponding, respectively, to said primary and secondary grooves; said primary groove and aperture operating during all recoil lengths, and said secondary groove and aperture being of less cross sectional area than the aforesaid primary groove and aperture, and being out of operation during the shortest recoil.

40. 2. A device for adjusting the recoil length in fluid recoil brakes, having a piston and a part cooperating with the piston, said part being provided with a primary helical groove and a secondary helical groove, and said piston with a primary aperture and a secondary aperture corresponding respectively, to said primary and secondary grooves; said primary groove and aperture operating during all recoil lengths, and said secondary groove and aperture being out of operation during the shortest recoil; said primary groove being approximately twice as wide as said secondary groove.

3. A device for adjusting the recoil length in fluid recoil brakes, having a piston and a part cooperating with the piston, said part being provided with a primary helical groove and a secondary helical groove, and said piston with a primary aperture and a secondary aperture corresponding, respectively, to said primary and secondary grooves; said primary groove and aperture operating during all recoil lengths, and said secondary groove and aperture being out of operation during the shortest recoil; said primary groove having greater pitch than said secondary groove.

4. A device for adjusting the recoil length in fluid recoil brakes, having a piston and a part cooperating with the piston, said part being provided with a primary helical groove and a secondary helical groove, and said piston with a primary aperture and a secondary aperture corresponding, respectively, to said primary and secondary grooves; said primary groove and aperture operating during all recoil lengths, and said secondary groove and aperture being out of operation during the shortest recoil;

5. A device for adjusting the recoil length in fluid recoil brakes, having a piston and a part cooperating with the piston, said part being provided with a primary helical groove and a secondary helical groove, and said piston with a primary aperture and a secondary aperture corresponding, respectively, to said primary and secondary grooves; said primary groove and aperture operating during all recoil lengths, and said secondary groove and aperture being out of operation during the shortest recoil;

6. A device for adjusting the recoil length in fluid recoil brakes, having a piston and a part cooperating with the piston, said part being provided with a primary helical groove and a secondary helical groove, and said piston with a primary aperture and a secondary aperture corresponding, respectively, to said primary and secondary grooves; said primary groove and aperture operating during all recoil lengths, and said secondary groove and aperture being out of operation during the shortest recoil; said primary groove having approximately double the width of and a greater pitch than said secondary groove.

The foregoing specification signed at 10 Barnen, Germany, this 16th day of Dec., 1914.

NORBERT KOCH. [L.S.]
